UNITED STATES PATENT OFFICE.

PETER COOPER HEWITT, OF NEW YORK, N. Y., ASSIGNOR TO COOPER HEWITT ELECTRIC COMPANY, A CORPORATION OF NEW YORK.

VAPOR ELECTRIC LAMP AND CONNECTION.

1,014,705.

Specification of Letters Patent.

Patented Jan. 16, 1912.

Application filed March 19, 1903. Serial No. 148,504.

To all whom it may concern:

Be it known that I, PETER COOPER HEWITT, a citizen of the United States, and resident of New York, county of New York, 5 State of New York, have invented certain new and useful Improvements in Vapor Electric Lamps and Connections, of which the following is a specification.

The present invention relates to an electrical apparatus in which a suitable gas or vapor inclosed in a transparent container is made luminous by the passage of electric current. The type of apparatus illustrated is adapted for various uses, and the novel 10 features of the said device will be explained in the specification and fully set forth in the claims.

The illustrations, Figures 1 and 2, show similar types of electrical apparatus of this 20 sort, the main difference appearing in the electrical connections for the lamp.

The container consists of a tube, 1, of glass or other transparent material, provided with electrodes, 2, 3, and 4. The electrode 2 is 25 here shown as a body of solid conducting material such as iron, while the electrodes 3 and 4 appear as small masses of mercury. Any suitable materials may be substituted for those named.

30 The electrodes 2 and 4 are mounted at the opposite ends of the tube 1, and the electrode 3 is contained in a small pocket, 5, formed on the container 1 about midway of its length. The device is provided with a 35 chamber 6 at the top serving as a cooling or condensing chamber whereby the vapors formed in the operation of the lamp are condensed and the general capacity of the device for radiating heat is increased.

40 In Fig. 1, the electrodes 2 and 3 are connected with the positive side of an electric circuit and the electrode 4 with the negative side. In Fig. 2, the electrode 2 is positive and the electrodes 3 and 4 are negative.

45 I may interpose suitable resistances or inductance devices, 7 and 8, in the wires leading to the electrodes, as may be desired or required for different uses of the apparatus and for steadyng the operation thereof.

50 In the lamp illustrated in Fig. 1, it is found that the vapor in the lower part of the lamp is denser than in the upper part, the quantity of current passing through the said lower half being approximately

double that passing through the upper half. 55 The apparatus may be used in testing the operations which take place in an inclosed gas or vapor carrying electric current, or it may be utilized for producing different effects in different parts of a single inclosing 60 chamber.

Fig. 2 is made use of simply to illustrate a different set of connections for the electrodes, and it will be understood that these connections may be still further varied to 65 suit different requirements, at the will of the operator.

In operating this lamp the mercury which is condensed in the chamber 6 is redistributed for condensation, passing down the 70 tube into the pocket 5 and overflowing from that pocket into the lower part of the tube and there re-constructing the electrode 4. This is found to be a valuable feature of the lamp and is one of the features constituting the present invention. For lighting these tubes applicant uses the ordinary direct current supply systems at from 100 to 200 volts, the tube being started by an instantaneous wave of high potential, generated by a Wehnelt interrupter or any convenient appliance. Although in starting up a higher voltage than normal is sometimes used to start the discharge through the tube, the tubes can be put in operation 85 without having recourse to high starting voltages.

The devices of the present invention possess the quality of negative electrode or initial reluctance to the flow of current. 90

I claim as my invention:

1. A vapor electric device comprising a vertical tubular portion, a condensing chamber at the top thereof inclosing a solid anode, a vaporizable cathode at the bottom 95 thereof and a pocket intermediate of said tubular portion adapted to contain vaporizable material and thus act as an electrode and so disposed as to receive vaporizable material condensed in the said condensing 100 chamber and to discharge any excess of vaporizable material to the said cathode.

2. A gas or vapor electric apparatus comprising a tubular portion, a plurality of vaporizable electrodes, a solid anode located 105 at the top of said tubular portion, a condensing chamber around said anode and means for returning condensed vaporizable

- material from electrode to electrode by steps through the length of said tubular portion.
3. A gas or vapor electric apparatus, comprising a vertically disposed tubular portion, a solid anode therein located near the top thereof, a vaporizable cathode therein located near the bottom, together with an intermediate electrode located in a lateral extension of the said tubular portion.
- 10 4. A gas or vapor electric apparatus, comprising a vertically disposed tubular portion, a solid anode therein located near the top thereof, a vaporizable cathode therein located near the bottom, together with an intermediate electrode located in a lateral extension of the said tubular portion, and means for connecting said intermediate electrode to the said anode through a resistance.
- 15 5. A gas or vapor electric apparatus, comprising a vertically disposed tubular portion, a solid anode therein located near the top thereof, a vaporizable cathode therein located near the bottom, together with an intermediate electrode located in a lateral extension of the said tubular portion, and
- means for connecting the intermediate electrode with one of the first named electrodes.
6. A gas or vapor electric apparatus, comprising a suitable container, an anode and a vaporizable reconstructing cathode therein, together with a second anode coöperating with the said cathode and located outside of the current path between the first named anode and cathode, 30 said second anode being connected through a resistance with the lead of said first named anode.
7. A gas or vapor electric apparatus, comprising a suitable container, an anode and a cathode therein, together with a second anode coöperating with the said cathode and located outside of the current path between the first named anode and cathode, said second anode 35 being connected through a resistance with the lead of said first named anode.

Signed at New York, in the county of New York, and State of New York, this 17th day of March, A. D. 1903.

PETER COOPER HEWITT.
